(57) **CLAIM**

The ornamental design for a mount socket for use in vehicle dash mounted equipment, as shown and described.

DESCRIPTION

FIG. 1 is a perspective view of a mount socket for use in vehicle dash mounted equipment showing my new design;

FIG. 2 is a rear view thereof; and,

FIG. 3 is an end view thereof.

In the drawings, the broken lines depict portions of a mount socket that form no part of the claimed design.
